US0D1035078S

(12) **United States Design Patent** (10) **Patent No.:** **US D1,035,078 S**
(45) **Date of Patent:** **** Jul. 9, 2024**

(54) **CLIP-ON READING LIGHT**

(71) Applicant: **ZHENGZHOU DEWENWILS NETWORK TECHNOLOGY CO., LTD.**, Zhengzhou (CN)

(72) Inventors: **Naiyao Zhao**, Zhengzhou (CN); **Yafei Jing**, Zhengzhou (CN); **Yahui Fu**, Zhengzhou (CN)

(73) Assignee: **ZHENGZHOU DEWENWILS NETWORK TECHNOLOGY CO., LTD.**

(**) Term: **15 Years**

(21) Appl. No.: **29/862,278**

(22) Filed: **Dec. 8, 2022**

(30) **Foreign Application Priority Data**

Oct. 8, 2022 (CN) 202230658753.7

(57) **CLAIM**

The ornamental design for a clip-on reading light, as shown and described.

DESCRIPTION

FIG. 1 is a perspective view of a clip-on reading light showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view showing a state of use thereof, shown without the clip; and,

FIG. 9 is a perspective view showing an exploded view thereof.

Broken lines in the drawings depict portions of the clip-on reading light that form no part of the claimed design.

1 Claim, 8 Drawing Sheets
